UNITED STATES PATENT OFFICE.

FRED L. METCALF, OF PLAINFIELD, NEW JERSEY.

ROTARY ENGINE.

1,266,298.

Specification of Letters Patent. Patented May 14, 1918.

Application filed February 9, 1918. Serial No. 216,149.

To all whom it may concern:

Be it known that I, FRED L. METCALF, a citizen of the United States, residing at Plainfield, in the county of Union and State of New Jersey, have invented a certain new and useful Improvement in Rotary Engines, of which the following is a specification.

The invention is a rotary engine, wherein the motor fluid may be used expansively. The cut off mechanism is controlled by the rotor to confine the motor fluid in the cylinder after it has followed the rotor over a predetermined fraction of its stroke. The rotor is formed of two concentric cylindrical shells, one of which is a cam fast on the rotor shaft, and the other is a sleeve rotatable on said cam. There are ports in both cam and sleeve. The rotor has a head at each end, one of said heads having a port which is always in communication with the motor fluid inlet duct. The motor fluid then passes through the cam, and when the ports in cam and sleeve are in correspondence escapes to the cylinder, entering a space between the rotor and a swinging abutment, which at one edge is hinged to the cylinder and at the other edge is hinged to the sleeve. The unbalanced pressure in said space causes the rotor to begin its stroke, and to continue until the ports are no longer in correspondence, when the motor fluid is cut off—the confined fluid then continuing to actuate the rotor by reason of its expansion. The exhaust duct remains throughout the stroke open for the escape of fluid in advance of the rotor, the escape of the working fluid from the cylinder chamber during the period of the stroke being prevented by contact between the rotor sleeve and the interior surface of the containing cylinder. The final release of the fluid from the chamber is effected automatically by the arrival of the said line of contact at the anterior margin of the exhaust port, at the termination of the stroke shortly before the rotor has arrived again at its initial position, and the ensuing retreat of the rotor sleeve from its contact with the external cylinder. In the manner described, the rotor itself thus constitutes both the supply and exhaust valves of the engine. The period of cut off may be adjusted to suit a desired degree of expansion.

In the accompanying drawings—

Figure 1 is a longitudinal section of my 55 rotary engine.

Fig. 2 is a cross section on the line II II of Fig. 1.

Fig. 3 is a perspective view of the rotor cam. 60

Fig. 4 is a perspective view of the rotor sleeve.

Fig. 5 is a perspective view of the swinging abutment.

Figs. 6, 7, 8, 9 are cross sections on the line 65 VI VI of Fig. 1, showing the rotor in different positions in its stroke.

Fig. 10 is a side elevation of the rotor shaft, rotor cams and heads on said cams.

Fig. 11 is a section on the line XI XI of 70 Fig. 10.

Fig. 12 is a face view of the head 29, showing the flange 34 thereon and shaft 10 in section.

Similar numbers of reference indicate like 75 parts.

1 is the bed of the engine, having flanges 2 bolted to suitable supports 3. Entering the bottom of said bed and disposed in line transversely across the same are the motor 80 fluid inlet duct 4 and the exhaust duct 5. The cylinder 6 contains two engines, the rotors of which are set 180° apart, as will be hereafter explained. Bolted to the ends of the cylinder 6 are heads 7, 8, which are 85 alike. Said heads are each preferably substantially cup-shaped. On the outer side of said heads are stuffing boxes 9, through which pass the rotor shaft 10. In the central portion of each head is an inward shouldered projection 11 which receives a bushing 12. The rotor shaft 10 is shouldered to fit against the ends of said bushings. 90

As the working parts of the two engines contained in cylinder 6 are alike, a description of the construction of said parts of one engine applies to both. 95

The rotor comprises the following parts: two cylindrical shells—namely; first, a hollow cylindrical cam 13, shown separately in 100 perspective in Fig. 3. Said cam is open at both ends, and has a longitudinal internal enlargement 14, in which is an opening 15 for the reception of shaft 10 which is keyed in said opening. The cam 13, which is thus 105 eccentrically supported on shaft 10, has in

its wall a quadrangular port 20. Second, a sleeve 21, shown separately in perspective in Fig. 4, in which the cam 13 rotatably fits. In the wall of said sleeve is a quadrangular port 22, here shown of greater circumferential length than port 20. On the sleeve 21 is a longitudinal projection 24, at the end portions of which are two lugs 25. The surface of the projection 24 between the lugs 25 is grooved and provided with channels 26 for the reception of packing.

The open ends of the respective rotors are closed by heads 27, 28, 29, 30, Figs. 1 and 10. The heads 27 and 28 close the ends of the rotor of the engine on the left of Fig. 1, and the heads 29 and 30 close the ends of the rotor of the engine on the right of Fig. 1. The heads 27 and 30 are alike, and the heads 28 and 29 are alike. The head 30 is a disk having its circumferential periphery outwardly stepped and enters the inwardly stepped wall or flange of the cup-shaped head 8. Clearances are left between the head 30 and the flange of head 8 for the reception of suitable packing. The opposite head 29 is also in circular disk form, and is similarly stepped.

Midway the length of the cylinder 6 and integral with the wall of said cylinder is a stepped circumferential rib 31, against one side of which the head 29 is seated, the similar head 28 being seated against the other side, and the faces of said heads within the rib meeting. Each head 27 and 30 has a port 32, surrounding which on the inner side of the head is a flange 33 which is received within the rotor cam 13. On the head 29 is a flange 34, similar to flange 33, which enters the opposite end of cam 13. The shaft 10 is shouldered to bear against the inner faces of the heads 27 and 30. The port 32 communicates with the hollow space within the head 8, and this space in turn, by the duct 35 in the engine bed, communicates with the inlet duct 4.

It will, therefore, be understood that motor fluid entering at the inlet 4 proceeds to the duct 35, to the hollow spaces within the heads 7, 8, and thence by the ports 32 to the interior of the rotor cam 13.

I will now describe the swinging abutments which are alike in the two engines.

One of these abutments is shown separately and in perspective in Fig. 5. It comprises a curved plate 36, on the concave side of which and extending from one edge thereof is a projection 37 which enters and fits the port 22. The object of the projection 37 is simply to fill the port 22, and so eliminate a space which otherwise would be filled by fluid. One edge of the abutment is grooved to receive the lugs 25 on sleeve 21. In the middle of said edge is a rounded lug 38 which fits in the groove of projection 24 and between the lugs 25 of the sleeve

21—these parts being hinged together by a pin 39 passing through the lugs 25 and 38. The rounded edge of abutment 36 is received in a groove in the engine bed. Near the edge 40 of the abutment is a longitudinal opening. A long pin 41, Fig. 1, bears at its ends against the inner faces of the cylinder heads 7, 8, and passes through the openings of both abutments 36. In this way the abutments 36 are hinged to the cylinder. The cams 13 of the two engines are united by headed bolts 42 which extend through openings in the enlargements 14 of said cams.

The operation of the parts can now be followed.

In Fig. 6 the port 20 in the rotor cam 13 is closed by sleeve 21. The duct 44 in the engine bed 1—which duct communicates with the exhaust duct 5—is open. This is the condition shown in Fig. 6, and also in the engine at the left of Fig. 1. At this time the rotor of the other engine on the right of Fig. 1 is in a position 180° different from that of Fig. 6. When the rotor begins to travel in the direction of the arrow *a*, the cam 13 then acts on sleeve 21 to swing upwardly the abutment 36, while at the same time turning in said sleeve to bring the ports 20, 22 into correspondence. The exhaust duct 44 is more widely opened. The motor fluid which, as already described, has passed through the port 32 into the rotor cam 13, now passes through the ports 20, 22 into the space 43, Fig. 7, which is just beginning to form below the rotor, pressing upon the abutment 36 and said rotor. The unbalanced steam pressure acts on the rotor to move it in the direction of the arrow *a*, as stated. The cam 13 turns within sleeve 21, until the ports 20, 22 are no longer in communication, and port 20 is closed by the sleeve 21. This is the condition shown in Fig. 8, from which it will be seen that the space 43 has now largely increased in size. The exhaust duct 44 is still more widely opened. But because the port 20 is closed, the motor fluid is cut off from space 43. Its expansion in said space now causes the further revolution of the rotor, during which the parts assume the position shown in Fig. 9, when the exhaust duct 44 is closed. Further revolution of the rotor brings the parts back to the position of Fig. 6.

For purposes of lubrication, I bore the shaft 10, as shown at 45, Fig. 1, closing the ends by screw plugs 46. Radial channels communicating with bore 45 lead the lubricant to the meeting surface of cam 13 and sleeve 21, and similar channels 49 lead the lubricant to the shaft bearings in heads 7, 8. In each stuffing-box I provide an opening 50, threaded at its upper end to receive a screw plug, through which opening liquid lubricant is introduced into bore 45.

The rotors of the two engines here shown are set 180° apart in order that one rotor may counterbalance the other. Should either engine be brought to a position of rest 5 at or about the second quarter of its revolution, as shown in Fig. 8, it may be necessary to deliver motor fluid into the space 43. This I may do by means of a valve 51, Fig. 8, which controls a small passage leading 10 into the engine cylinder from the inlet duct 35. A similarly placed valve is associated in like manner with the other engine. Because the rotors are 180° apart, one of the two will be situated between the location of 15 the valve 51 and its position, as indicated in Fig. 9, hence the admission of the motor fluid through one or the other valve starts both of the connected rotors. This expedient will, of course, be unnecessary if the 20 rotors of a plurality of engines having a common shaft are set at different angles.

It is to be noted that the admission and cut off of motor fluid is controlled by the ports in the rotor, and not by any extraneous valve governed by said rotor, so that 25 the rotor is substantially its own valve, which is opened or closed by the relative movements of the cam and sleeve. The timing of the cut off depends upon the relative 30 circumferential measurements of the said ports, and, therefore, by varying these measurements in designing a particular engine, a desired degree of fluid expansion is easily obtained.

35 I claim:

1. A rotary engine, comprising a cylinder having a motor fluid inlet and outlet, a rotor shaft, a rotor eccentrically supported on said shaft and comprising two concentric cylindrical shells, each shell having a port in its wall, the inner shell being in communication with said motor fluid inlet, and an abutment having one edge pivoted to said cylinder and its opposite edge pivoted to said outer shell.

40 2. A rotary engine, comprising a cylinder having a motor fluid inlet and outlet, a rotor shaft, a rotor, the said rotor comprising a hollow cylindrical cam on said shaft and a sleeve on said cam, there being ports in said

45 50 cam and said sleeve, heads on said rotor, one

of said heads having a port communicating with said motor fluid inlet, and a swinging abutment hinged at one edge to said cylinder and at its opposite edge to said sleeve.

3. A rotary engine, comprising a cylinder 55 having a motor fluid inlet, a substantially cup-shaped head on said cylinder communicating with said inlet, a rotor shaft in said cylinder, a rotor comprising a hollow cylindrical cam on said shaft and a sleeve on said cam, there being ports in said cam and said sleeve, heads on said rotor, one of said rotor heads closing the open end of said cylinder head and having a port, and a swinging abutment hinged at one edge to said cylinder 60 and at its opposite edge to said sleeve.

4. A rotary engine, comprising a cylinder having a motor fluid inlet and outlet, a rotor shaft, a rotor supported on said shaft and comprising a cam and a sleeve on said cam, 70 there being ports in said cam and sleeve, and a swinging abutment having one edge pivoted to said cylinder between said inlet and outlet and its opposite edge pivoted to said sleeve.

75 5. A rotary engine, comprising a cylinder, a circumferential rib therein, a rotor shaft, two rotors on said shaft, each rotor comprising a hollow cylindrical cam and a sleeve on said cam, and two heads on each of said 80 rotors, the adjacent heads of said rotors being seated on opposite sides of said rib.

6. A rotary engine, comprising a cylinder having a motor fluid inlet, a rotor shaft, a rotor formed of two concentric cylindrical 85 shells, each having a port in its wall, the inner shell communicating with said inlet, means for relatively moving said rotor shells to bring said ports into and out of correspondence to control the passage of motor 90 fluid from said rotor to said cylinder, and means for conveying lubricant to the joint between said shells.

In testimony whereof I have affixed my signature in presence of two witnesses.

FRED L. METCALF.
